FLOUR SIFTER

Filed March 29, 1935

UNITED STATES PATENT OFFICE

2,126,982

FLOUR SIFTER

Charles Andrews and Wilbur Hannon, Rockford,
Ill., assignors to The Washburn Company,
Worcester, Mass., a corporation of Massachusetts

Application March 29, 1935, Serial No. 13,686

5 Claims. (Cl. 209—358)

This invention relates to sifters generally, and is particularly concerned with improvements in flour sifters for domestic use.

The principal object of the invention is to provide a flour sifter of simpler and more durable construction than has been available in the past, and one which presents a better appearance.

One of the important features is the novel construction whereby the handle is fastened to the cylindrical body of the sifter by encircling bands so as to fasten the handle more firmly and, at the same time, actually reenforce the sifter, instead of placing a strain upon the sheet metal body thereof. One of the bands serves moreover to cover up the bent-over lugs of a cross-bar where the bar is fastened to the side walls, thus leaving nothing exposed to detract from the appearance of the sifter.

The invention is illustrated in the accompanying drawing, in which—

Figure 1 is a view partly in side elevation and partly in central vertical section of a flour sifter made in accordance with the invention;

Fig. 2 is a sectional detail on the line 2—2 of Fig. 1, and

Fig. 3 is a cross-section on the line 3—3 of Fig. 1.

The same reference numerals are applied to corresponding parts in these views.

The sifter comprises a substantially cylindrical sheet metal body or container 5, open at the top and bottom, and arranged to have a U-shaped handle 6 fastened to one side thereof so that the sifter can be operated by means of the knob 7 while it is held by the handle, in the usual way. The handle, in accordance with this invention, has its ends 8 and 9 abutting the side of the body, and two sheet metal bands 10 and 11 encircle the body between pairs of outwardly projecting annular beads 10' and 11', respectively, formed on the body, the bands having their ends bent outwardly, as indicated at 12, and suitably secured to opposite sides of the handle, as by rivets 13. The bands are drawn tightly onto the body to prevent turning relative thereto, and, in that way, serve to reenforce the body, the seam of which appears at 14. The annular beads 10' and 11' prevent displacement of the bands up or down relative to the body, at the same time shielding the cut edges of the sheet metal bands. The resulting structure presents a pleasing and attractive appearance, especially when the bands and handle are made in a color or finish to match one another and in contrast to the body 5. For example, the bands 10 and 11 and handle 6 may

be painted black to stand out in sharp contrast to the tinned sheet metal body. The upper band 10 also serves to conceal the lugs 14 on the cross-bar 15 which project through slots 16 in the side wall of the body 5 and are bent over, as indicated in Fig. 2. In that way, nothing to detract from the appearance of the sifter is left exposed.

The bar 15 is of sheet metal and made V-shaped in cross-section for rigidity. It has a center hole therein to provide an upper bearing within the body 5 for the shaft 16, whose lower portion bears in grommets 17 in the sieves 18. The lower portion of the shaft is flattened to drive agitators 19 held yieldingly in engagement with the screens of the sieves by coiled compression springs 20, in the manner set forth in our copending application Serial No. 740,607, filed August 20, 1934. The springs 20 for the bottom and middle sieve bear against the grommets 17 of the adjacent sieve, but the longer spring 21 for the upper sieve extends up to the cross-bar 15 for its abutment. The body of each sieve is formed by a sheet metal ring or hoop 22, as disclosed in the other application, the rings being disposed in stacked relation, in edge to edge abutment to one another circumferentially. An annular external groove 23 is formed in the body 5 to provide an internal annular shoulder for abutment with the ring 22 of the top sieve, whereby to locate the sieves as shown. The lowest annular bead 11' provides an internal annular groove 24 beneath the ring 22 of the bottom sieve, and a spring type retainer 25 is arranged to be compressed sufficiently to enter the bottom of the sifter and to then expand into the groove 24 to releasably secure the sieves in place. The retainer 25, in accordance with the present invention, is of spring wire construction bent into a triangular or heart shape with the free ends 26 crossed at the apex of the triangle and welded at 27. The free ends are thus spaced enough to receive the seam 14 therebetween when this portion of the retainer is inserted in the groove 24, thus holding the retainer against turning within the body 5. The two arcuate portions 28 at the base of the triangle are connected by an arcuate base portion 29. The retainer can be quickly and easily entered and as easily removed, although it holds the sieves securely in place once it is properly entered. To insert the retainer, one merely places the ends 26 in the groove 24, straddling the seam 14, whereupon the rest of the retainer is pressed into the bottom of the sifter and snapped into the groove. The arcuate por-

tion 29 gives sufficiently in this operation to allow the small amount of compression required to slide the retainer into place, and the retainer snaps into the groove due to its expansion. In 5 the removal of the retainer, one need only force the arcuate portion 29 in the direction of the apex 27 enough to draw the portions 28 of the retainer toward each other to disengage one or both of these portions from the groove 24, whereupon the retainer is removable. Then, upon removal of the cotter pin 30 from the lower end of the shaft 16, the sieves 18 can be removed. The fact that the ends of the wire forming the retainer 25 are welded at 27 insures permanence 10 of form and the desired spring action at all times.

The knob 7, as clearly appears in Fig. 1, is rotatably secured to the crank end 31 of the shaft 16. The knob is of wood, or any other suitable material, and has an axial bore 32 large enough 20 to freely receive the flattened or upset end 33 of the shaft. A short sleeve 34 is rotatable on the end 31 of the shaft and retained by the portion 33 thereof. The sleeve is formed to provide a fluted portion 35, which, when the knob 7 is pressed down onto the sleeve 34, cuts grooves in 25 the knob so as to fasten the knob securely onto the sleeve and leave no likelihood of the knob working loose. This fastening for the knob leaves nothing of objectionable appearance exposed, and 30 the knob is at the same time freely rotatable and yet very securely held in place.

We claim:

1. In a sifter having a vertically disposed rotary drive shaft, the combination of a substantially cylindrical sheet metal body open at the top and bottom, a cross-member within said body adjacent the top thereof providing bearing support for the shaft and having end portions extending through and secured to the side walls of said body, a handle having an end portion to be fastened to said body, and a sheet metal handle mounting band secured to said handle and encircling the body in substantially the same plane with the aforesaid cross-member and covering the projecting end portions thereof to conceal the same.
2. In a sifter having a vertically disposed rotary drive shaft, the combination of a substantially cylindrical sheet metal body open at the top and bottom, a cross-member within said body adjacent the top thereof providing bearing support for the shaft and having end portions extending through and secured to the side walls of said body, a handle having an end portion to be fastened to said body, and a sheet metal handle mounting band secured to said handle and encircling the body in substantially the same plane with the aforesaid cross-member and covering the projecting end portions thereof to conceal the same, said body being formed to provide an outwardly projecting annular bead above and in circumferential engagement with the upper edge of said band, for the purpose described.
3. In a sifter having a vertically disposed rotary drive shaft, the combination of a substantially

cylindrical sheet metal body open at the top and bottom, a cross-member within said body adjacent the top thereof providing bearing support for the shaft and having end portions extending through and secured to the side walls of said body, a handle having an end portion to be fastened to said body, and a sheet metal handle mounting band secured to said handle and encircling the body in substantially the same plane with the aforesaid cross-member and covering the 10 projecting end portions thereof to conceal the same, said body being formed to provide outwardly projecting annular beads above and below the band and in circumferential engagement with the edges thereof, for the purpose described.

4. In a sifter, the combination of a substantially cylindrical sheet metal body open at the top and bottom, plural removable sieves each comprising a circular sheet metal ring fitting slidably in said body and supporting a screen in transverse 20 relation to said body, the rings being arranged in edge to edge relation whereby to space the screens vertically in said body, means engaging the upper sieve ring to prevent upward displacement of the sieves in the body, a handle having spaced end 25 portions for attachment to the outside of the body, handle mounting bands secured to the end portions of the handle and encircling the body, said body being formed to provide an annular outwardly projecting bead in engagement with the lower band to prevent longitudinal displacement of the band relative to the body, said bead providing an internal annular groove in a plane 30 below the lower sieve ring, and means removably engaged in said groove and abutting the bottom of the lower sieve ring to retain the several sieves in place in said body.

5. In a sifter, the combination of a substantially cylindrical sheet metal body open at the top and bottom, a plurality of removable sieves each comprising a circular sheet metal ring fitting slidably in said body and supporting a screen in transverse relation thereto, the rings being arranged in edge to edge mutual supporting relation whereby to space the screens vertically in said body, said body being formed to provide an annular inwardly projecting bead above the uppermost sieve in engagement with the upper edge of the ring thereof to prevent upward displacement of the stack of sieves in the body, a handle having spaced end portions for attachment to the outside of the body, bands encircling the body and having end portions secured to the end portions of said handle, said body being formed to provide an annular outwardly projecting beads above and below the lower band to prevent longitudinal displacement of the band relative to the body, one of said beads providing an internal annular groove in a plane below the lower sieve ring, and means removably engaged in said groove and abutting the bottom of the lower sieve ring to retain the several sieves in place in said body.

CHARLES ANDREWS.

CERTIFICATE OF CORRECTION.

Patent No. 2,126,982.

August 16, 1938.

CHARLES ANDREWS, ET AL.

It is hereby certified that error appears in the printed specification of the above numbered patent requiring correction as follows: Page 2, first column, line 42, claim 1, for the word "hand" read band; and that the said Letters Patent should be read with this correction therein that the same may conform to the record of the case in the Patent Office.

Signed and sealed this 1st day of November, A. D. 1938.

Henry Van Arsdale
